UNITED STATES PATENT OFFICE

2,481,936

DEVICE FOR HOLDING AND SETTING
JOINTER KNIVES

Maxwell A. Lord, Denver, Colo.

Application May 16, 1947, Serial No. 748,482

1 Claim. (Cl. 51—218)

1 This invention relates to a device for use in sharpening and setting jointer knives. It is exceedingly difficult with ordinary equipment to obtain the proper bevel and a perfectly straight edge on a jointer knife and without straight edges the knives cannot operate efficiently.

The principal object of this invention is to produce a compact, easily used and highly efficient device which will enable an unskilled operator to obtain a perfect bevel and perfectly straight edge upon a jointer knife in a conventional drill press.

It is also exceedingly difficult to set the knives in a jointer head in absolute alignment with the rear jointer table and unless the knives are so set they cannot of course produce efficient work.

Another object of this invention is to so construct the device that it will enable anyone to set the knives in a jointer head so that every knife and every portion of the edge of every knife will travel in a perfect cylindrical plane about the axis of the head in tangential alignment with the rear table of the jointer.

A further object of the invention is to so construct the device that it may be used on jointer knives of various lengths and widths and of various thicknesses and types without change in the device.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a fragmentary longitudinal section through a conventional jointer illustrating a side view of the invention as it would appear in use thereon:

Fig. 2 is a perspective view of the improved device for sharpening and setting jointer knives;

Fig. 3 is a cross section through the device, taken on the line 3—3, Fig. 2, illustrating it as it would appear placed in a conventional drill press for sharpening purposes;

Fig. 4 is a detail vertical section through a knife setting plunger employed in the improved device; and

Fig. 5 is a cross section taken on the line 5—5 Fig. 2.

2 In Fig. 1 typical portions of a conventional jointer are designated by numeral as follows: front table 10; rear table 11; jointer shaft 12; jointer head 13; jointer knife 14; jointer knife clamping block 15; and jointer knife clamp screws 16.

In Fig. 3 portions of a conventional drill press arranged for grinding and sharpening the knives 14 with the use of the improved device are designated by numeral as follows: drill chuck 17; cupped grinding wheel 18 and work table 19.

The improved sharpening and setting device comprises an elongated frame block 20 terminating at each extremity in clamping feet 21 and 22, each provided with an attachment bolt slot 23. An inclined surface 24 is formed along the front of the frame block 20. The incline of this surface 24 corresponds to the incline of the bevel of a conventional jointer knife. A longitudinally extending locating groove 25 is formed along the bottom of the inclined surface 24 and a projecting ledge portion 26 extends outwardly from the groove 25.

A clamping bar 27 rests against the ledge portion 26 and is provided with a longitudinally extending flange 28 which rests in the bottom of the groove 25. The clamping bar 27 is for the purpose of clamping one of the knives 14 against the inclined surface 24. The clamping is accomplished by means of clamp screws 29 the heads of which bear against the bar 27 and the shanks of which are threaded on an incline into the frame block 20.

The blade to be sharpened rests upon projecting screw extremities 30 formed on blade adjusting screws 31. The screws 31 are threaded on an incline through the ledge portion 26 in the plane of the blade 14 and the extremities 30 extend through notches in the flange 28 so as to contact the back edge of the blade. The screws 31 are adjusted to bring the sharp edge of the knife 14 to a perfect level. The clamp screws 29 are then tightened to clamp the knife 14 in the adjusted position.

The sharpening is accomplished by placing the frame block 20 upon the drill press work table 19 below the grinding wheel 18 as shown in Fig. 3. The frame block 20 may be bolted to the table 19 by means of suitable attachment bolts through the slots 23 if desired. The drill press is adjusted to hold the grinding wheel 18 in a pre-set vertical position. The table 19 is then swung back and forth beneath the grinding wheel causing the latter to grind the bevel on the blade on a perfect level.

After the blades have been ground they must be set in the jointer head 13 in perfect alignment with the rear table 11. This is accomplished by means of a setting plunger 32 which is vertically 5 slideable in a plunger guide 33. The plunger guide is threaded at its lower extremity as shown in 34, and is threaded through the foot 22 with the plunger 32 projecting therebelow as shown in Fig. 1.

A plunger rod 35 extends upwardly from the plunger 32. A piston portion 36 is formed on the rod 35 above the plunger 32. A stop pin 37 extends through the guide 33 between the plunger 32 and piston 36 to limit the vertical movement of the rod 35. A compression spring 38 is positioned in the guide 33 above the piston 36 and acts to constantly urge the plunger 32 downwardly. The length of the rod 35 is accurately formed so that its upper extremity will align perfectly with the upper extremity of the guide 33 when the bottom of the plunger 32 is in perfect alignment with the bottom of the frame block 20. In use, the plunger is set over the one extremity of the knife 14, as shown in Fig. 1, and the knife is raised or lowered until the upper extremity of the rod 35 aligns perfectly with the upper extremity of the holder 33. The plunger is then moved to the other extremity of the knife and a similar adjustment is made after which the knife clamping screws 16 are tightened to lock the knife in place in the head 13. It is essential that the path of the edges of the knives be in exact alignment with the top of the rear table 11. This alignment is assured with this device since the upper extremity of the rod 35 will only align with the upper extremity of the holder 33 when the bottom of the plunger 32, which is resting on the knife 14, aligns with the bottom of the block 20. Since the bottom of the block 20 is resting on the rear table 11 the desired exact alignment is assured.

The bottom of the ear 22 is cut upwardly, as shown at 39, so as to be above the general plane of the bottom of the block 20 so as not to be struck by the knives 14. The guide 33 is prefer-

ably knurled as shown in 40 to provide a convenient finger grip.

While a specific form of the improvement has been described and illustrated herein, it is desired to be understood that the same may be varied, within the scope of the appended claim, without departing from the spirit of the invention.

Having thus described the invention, what is claimed and desired secured by Letters Patent is:

A device for use in sharpening jointer knives comprising: an elongated frame block; feet extending oppositely outward from the extremities of said frame block, the bottom surface of said frame block and said feet being co-extensive; a 15 forwardly and downwardly inclined forward surface on said frame block; an upwardly and forwardly extending projecting ledge extending longitudinally along the lower edge of said inclined surface at right angles thereto, there being a longitudinal groove between said ledge and said inclined surface; a clamping bar extending along said inclined surface; a longitudinally extending flange along said clamping bar projecting into said groove; clamp screws extending through said clamping bar and into said frame block for clamping said clamping bar against a jointer knife lying on said inclined surface; and adjusting screws threaded through said ledge, said screws lying in the plane of said jointer knife so as to contact the lower edge thereof, said flange being notched for the said passage of said screws.
